UNITED STATES PATENT OFFICE.

ERNEST A. DE WOLF, OF CRANSTON, RHODE ISLAND, ASSIGNOR TO UNIVERSAL WINDING COMPANY, OF BOSTON, MASSACHUSETTS, A CORPORATION OF MASSACHUSETTS.

CREEL.

Application filed July 8, 1927. Serial No. 204,369.

This invention relates to creels for holding cops, cones or packages to deliver yarn, thread and other strand material therefrom in various processes of the textile art.

5 A principal object of the invention is to provide a creel adapted to support a plurality of non-rotatable cops, cones or packages to adapt the yarn to deliver over the end thereof at a high rate of speed and with a uniform tension on all of the ends.

Another important object of the invention is to provide a creel adapted to hold a reserve supply of yarn or thread connected to the delivering supply and arranged in such 15 manner that when the latter is exhausted the yarn will be taken from the reserve supply so that the warping or other operation to which the material is delivered may be continuous without arresting it to doff the empty cop-holders and to creel a new set of supplies.

Another object of the invention is to provide a creel from which the material delivers continuously without the necessity for 20 repeatedly threading up the tension-devices, and on which the supply-cops or cones may be more conveniently and expeditiously creeled while the warping or other operation is under way.

30 Another object of the invention is to provide a creel from which the yarn can be delivered down to the last end on the supply-cop or package without wastage from yarn left on the holders or without requiring rewinding of the undelivered ends.

Another object of the invention is to provide means on the creel for preventing the accumulation of lint, specks, motes, or loose 40 bits of yarn on the strand material while the ends are delivering from the supply packages.

Further objects of the improvement are, in general, to provide a creel from which the yarn, thread or other strand material may be 45 warped or transferred at maximum speed without stoppages for doffing, re-creeling or piecing up while at the same time delivering the strands under a more constant and uniform tension to improve the quality of the finished product.

The present improvements may be embodied in a creel having a form of construction such as described in the following specification and illustrated by way of

example in the accompanying drawings. In 55 the drawings:

Fig. 1 is a plan view of the improved creel shown as embodied in a preferred form of construction;

Fig. 2 is an elevation of the forward part 60 of the creel shown in slightly larger scale and illustrating the arrangement of the yarn-supplies thereon;

Fig. 3 is a still further enlarged detailed view showing several of the yarn-supplies in 65 the relation they assume on the creel and illustrating the tension-devices used in connection therewith;

Fig. 4 is an enlarged view of several of the 70 yarn-supplies shown in elevation as viewed from the back of the creel frame;

Fig. 5 is an enlarged detailed view of the mounting for one of the yarn-supplies;

Fig. 6 is a plan view of a portion of the 75 mounting; and

Fig. 7 is a detailed view of one of the separator-rods through which the strands are guided at the front or apex end of the creel.

Referring first to Figs. 1 and 2 of the drawings, the preferred form of construction 80 of the invention as herein described and illustrated comprises a V-shaped creel constituted by two wings 2—2 extending in opposite angular relation. Each wing 2 is preferably constructed as a framework or grill 85 constituted by vertical rods or uprights 3 and 4 supported in socketed feet 5 which are screwed or otherwise suitably fastened to the floor. The framework of the wings 2 is made double with the rods or uprights 3 and 4 arranged in two parallel planes spaced a short distance apart. The two rows of uprights are connected by horizontal tie-rods or longitudinal stringers 6 which pass through T-shaped bearings or brackets 7 secured to 90 the top of the uprights 3 and 4, see Fig. 2. The two opposite parts of the double framework or wings 2 are connected at the top by cross-braces 8 having bearings at the end of 95 their arms embracing the tie-rods 6 and secured thereto by set-screws or other means. Lateral braces 9 of graduated length extend between the two wings 2 of the creel to further reinforce the structure and hold the wings in inclined relation. The wings 2 100 may be braced from the floor by angular struts 10 and 11 which are attached to the forward and rearward ends of the horizontal

105

tie-rods 6 and supported at the bottom in socketed step-bearings 12. As shown in Figs. 1 and 2, another inclined strut or brace 13 extends downwardly from the forward 5 lateral brace or tie-rod 9 and is held to the floor in a step-bearing 12.

As illustrated in Figs. 2, 3 and 4, the rearward uprights 3 of the framework or wings 2 are of heavier construction than the 10 forward rods 4, being adapted to support the yarn-supplies C which are preferably in the form of cross-wound cones. These cones of yarn may be wound by any suitable method and preferably they are supported on 15 wooden holders 15 provided with axial bores 16 for receiving the spindles or mandrels 20 which mount the cones on the creel. It will be noted from Figs. 3 and 4 that each 20 cone-holder or wooden carrier 15 has a peripheral groove 18 in its larger end which is employed for a purpose as later explained; and also a circumferential groove 17 on the interior of its bore 16 by means of which the 25 holder is held on the spindle 20.

25 The improved means for supporting the cops, cones or packages C on the creel consists essentially of a swinging arm 21 carrying the cop-spindle 20 and having a hub or bearing 22 which turns loosely on the 30 upright or rod 3. The spindle 20 projects at substantially right-angles to the end of the arm 21 and is formed with a lip or abutment 23 adapted to engage the internal groove 17 in the bore of the carrier 15 to retain the 35 cop in place on its support.

The arm 21 is held on the vertical rod 3 by means of a collar 25 against which the end of its hub 22 bears. The collar 25 is adjustable vertically on the rod 3 to locate 40 the cone-holder in proper relation with respect to its respective tension-device, the collar being secured in place by any suitable means such as a set-screw 24. The collar 25 also provides means for holding the arm 45 21 in proper angular relation with respect to the rod 3 while adapting it to be swung back into the position illustrated by dotted lines in Fig. 3 to facilitate the placing of the cone on the spindle 20 or the doffing of 50 the empty carrier therefrom. The arrangement of these parts is illustrated in detail in Figs. 5 and 6, from which it will be observed that the collar 25 is provided with two lugs or fingers 26 and 27 against which 55 the arm 21 strikes as it swings one way or the other around the rod 3. The collar 25 is also formed with a V-shaped groove or depression 28 in its upper face which is adapted to be engaged by a tapered lug or 60 abutment 29 on the under side of the hub 22. When the arm 21 is swung into the position shown by full lines in Figs. 3 and 65 4 it will bring up against one of the stop-fingers 26 on the collar 25 and its lug 29 will drop into the V-shaped depression 28

on the upper side of the collar. This engagement of the lug 29 with the depression 28 provides a detent to hold the arm 21 normally in position with its cop or cone properly located with relation to its respective tension-device in the manner and for the purpose as hereinafter more fully explained. When the arm 21 is swung back into doffing position the lug 29 will ride up out of the depression 28 and slide along 70 the top of the collar 25 until the arm strikes the other stop-finger 27. It will be noted from Figs. 3 and 4 that the series of arms 21 spaced vertically on the rod 3 are arranged in alternate relation, one arm projecting to the left of the rod and the next arm to the right and so on as viewed from the back of the creel wing. To conform to this arrangement of the arms 21 the collars 25 are each formed with grooves or recesses 75 28 on their upper and lower surfaces so that they may be reversed in position as shown in Fig. 4 when employed with the alternate right- and left-hand arrangement of the arms 21.

90 The tension-devices 30 for applying tension to the yarns or threads delivering from the cones C are mounted on the smaller forward rods 4 of the wings 2. Any suitable form of tension-device may be used, but I 95 prefer to employ a disk-tension comprising opposed disks 31 mounted on pins or studs 32 projecting upwardly from brackets 33. The brackets 33 have jaws 34 adapted to embrace the rods 4 and set-screws 35 may be 100 employed to clamp them in place thereon as shown in Figs. 3 and 4. Each bracket 33 is provided with a guiding-hook 36 through which the strand of yarn y draws from the nose of the cone C. The strand is then led 105 between the tension-disks 31 and around the pin 32 and thence draws out around a second guide-hook 37 on the bracket 33. The 110 yarns from the whole series of cones are led forward toward the apex end of the creel and the ends leading from each horizontal row of tension-devices are threaded through a separator 40 projecting horizontally from the forward upright 41. These separators 115 40 are alined with the rows of tension-devices 30, there being one for each row as shown in Fig. 2, and each separator is provided with a series of porcelain thread-eyes 42 through which the yarns draw. In this way the ends from each row of supplies are 120 held in alinement in a single bank so as to render it easy to inspect the multiplicity of strands to detect a missing or broken end. From the separators 40 the ends lead forward to the warping or other machine in 125 which they are to be converted, the creel being adapted for delivering the yarn to section-beams for beam twisting, slashing, or weaving, or to a ball warper for balling 130 the material.

In handling and converting yarn, thread or the like at high speed considerable trouble is experienced from the accumulation of lint, fluff, fly, dust, specks and motes on the running yarn. There is necessarily a certain amount of lint generated in all processes of handling or treating yarns and where a very large number of ends are being treated, such as in a creel, a considerable amount adheres to the yarn, forming slubs and bunches thereon, and running through the beam causes defects in the finished product. With the present improved creel the tension-device acts to clear the yarn of much loose fluff, lint, specks and other adhering matter, and this is eventually thrown off into the air and taken up again by the yarn as it passes through the creel to the warper. Such conditions are present with practically all forms of creels, but in my present improved device means are provided for eliminating this source of trouble.

I have found that by setting up an air current around the yarn-supplies and their delivering ends I may hold the lint, fluff and fly in suspension in the atmosphere to prevent it from collecting on the yarn or thread. For this purpose I make use of fans or blowers, preferably electric fans which are mounted on both wings of the creel in front and above the tension-devices. Conveniently I may employ oscillating fans 43 mounted on arms or brackets 44 which are fastened to the top of the vertical uprights or rods 4. The fans 43 are suitably connected to light sockets or outlets to supply current through plug-cords or wiring, not herein shown, and as they oscillate in the manner indicated in Fig. 2 a current of air will be blown down across the yarns leading forward from the various tension-devices at the forward side of each creel-wing. I have found that three fans on each side of the creel are usually sufficient to produce overlapping currents of air which will completely maintain the lint and fluff in suspension and prevent it from being deposited on and adhering to the yarns traveling through the creel to the warping machine. The method of operation of my complete device is as follows:

The cones C or other yarn packages are applied to the creel from the back of the wings 2, there being sufficient space therebetween to permit the operator to travel from one end to the other. The cones are taken from the winding machines, placed on suitable racks and carried in trucks to the creel and there mounted on the spindles 20, the arms 21 being swung back into the position illustrated by dotted lines in Fig. 3 to facilitate this operation. Each cone-carrier 15 is simply slipped on over its spindle 20 and when released will drop down in position to cause the lip 23 at the end of the

spindle to engage in the internal groove 17 in the bore of the carrier.

It has been explained that reserve packages of yarn are applied to the creel to provide that when the first package or cone is exhausted the yarn will continue to deliver from the reserve cone to avoid the necessity of stopping the warping operation to replenish the supply. Stated briefly, two cones are creelied for each end to be delivered to the warper so that the whole number of cones on the creel is twice the number of ends being warped. It will be noted by reference to Fig. 3 of the drawings that two adjacent cones in each horizontal row point toward a single tension-device 30, and the ends of the yarn in these two cones are tied or spliced together to provide for the continuous delivery therefrom. It has been noted that the wooden cone-holders or carriers 15 are formed with peripheral grooves at their base ends and these are used to contain a short length of yarn for splicing to the end of the reserve cones. When the winding is started the end of the yarn is wrapped or coiled a few times around the carrier 15 in the groove 18 and after the cones have been creelied this length of yarn is drawn off or unwound from the groove and tied to the end leading from the next cone in the series, or, in other words, the reserve supply. The ends from the associated cones are thus spliced together along the whole creel and the ends from the first cones are then threaded through the tension-devices 30 in the manner as previously explained.

After all of the ends have been spliced and the leading ends led through the tension-devices they are drawn forward toward the apex end of the creel and threaded through the eyes 42 in the separators 40. As illustrated in Fig. 1, the yarns from each horizontal row of delivering cones will lead forward in a mat or bank and, drawing through the separator 40, are thence led to the warping or other machine located in position in advance of the apex end of the creel. The large number of ends delivering from the creel will thus be separated into distinct rows or banks arranged one above another and converging at the back of the warping machine to be wound thereby on to the section-beam. This separation of the multiple ends in banks facilitates inspection so that the operator may more readily discover a broken yarn and stop the warping operation to piece up.

With the apparatus threaded up in the manner as above described the warping or other operation is started and carried on continuously except for such stoppages as are necessary for piecing up broken ends or for removing the full section-beams and applying empty beams to the warper. As the warping operation proceeds the yarn from

the first-delivering cone is eventually exhausted, but when this point is reached the end leading from the first cone to the reserve cone will be taken up, and thereafter the 5. yarn will deliver from the reserve cone until its supply is exhausted.

As the yarn from the first set of cones is exhausted the attendant simply creels a new set of cones in its place and splices the last 10. end from the delivering cone to the leading end of this newly creeled supply. While all of the cones will not run out at the same time still their exhaustion takes place within a comparatively short period, but, on the 15. other hand, it is not required to immediately creel a whole set of new supplies. That is to say, sufficient time will elapse before the exhaustion of the reserve cones already creeled to allow the operator to creel another 20. set in place of the first-exhausted ones. It will thus be seen that the warping-operation may be maintained continuously for as long as desired, dependent only upon the capacity of the section-beams in the warping machine. 25. In other words, no time is lost for doffing the exhausted cone-holders and re-creeling new supplies and hence the whole process may be carried on at a maximum speed with none of the machinery or appliances idle during the normal period of operation of the mill.

During the warping operation the yarns draw through the tension-devices 30 and a uniform tension is applied to all of the ends 35. without material fluctuation from start to finish of each cone. A much more uniform tension is thus secured than can be obtained in taking the yarn from unrolling supplies such as spools mounted to rotate on the 40. creel. For this reason the inherent elasticity of the yarn is preserved and a firm yet resilient section-beam is produced without loose ends or unduly tight ends therein. This improvement in the warping or beam- 45. ing operation results in a corresponding improvement in the ultimate fabric in which the yarn is incorporated. The retention of the yarns' elasticity is of particular importance in making tire cords or fabrics where 50. the elongation tests are most exacting. The uniformity of tension on the ends of yarn is also important as preventing straining or breaking the yarn, thus permitting warping at much higher speed with consequent economies 55. in the cost of the final product. The high speed of the warping is due in great measure to the fact that the yarn is drawn off from the supplies without rotating them, there being no inertia to overcome as is the 60. case when rotating spools are employed. This improved feature also obviates the necessity of slow starting and stopping of the warper. In spool creels the warper must be started slowly to overcome the inertia 65. of the spools, and likewise it must be stopped

gradually to prevent the spools from over-running and delivering an excess supply of yarn. The quick stopping of the warper is important in order that the broken ends may not be lost or run into the beam. The 70 usual troubles from "drop plies" and "draw-backs" on slashers is thus eliminated with a resultant saving in time and improvement in the finished product.

It has been noted that as another feature 75 of improvement means are provided on the present creel for obviating the trouble and defects caused by lint, fluff, fly and foreign substances collecting on the yarns. While the warping operation is being carried on 80 the fans 43 operate to blow a current of air downwardly across the yarns, and being oscillated back and forth these currents are caused to overlap to cover the whole space through which the ends draw. Through 85 this means lint, fluff, specks, motes and loose bits of yarn are blown off from the running ends and maintained in suspension so that they cannot be carried through the warper to the section-beam. The result is that the 90 yarn wound on the beam is much cleaner and clearer from lint and fluff or other foreign matter.

It will be observed that in addition to the advantages above pointed out the present 95 improved creel provides a most compact and efficient device for the purpose specified. The improved apparatus permits warping yarns at a maximum rate of speed, it having been demonstrated that a speed of approximately 350 yards per minute can be maintained continuously as compared with a customary warper speed of 50 to 60 yards per minute with previous methods. The improved creel also provides for high speed 100 winding on cross-wound cones, which gives an enormous saving over the slow spooling process. It has been demonstrated that including the preparation of the yarn from the winding to the warping there is a saving in 105 labor of from one-half to two-thirds, due principally to the fact that the warping operation may be carried on continuously. In addition to this there is a material saving in floor space, cost of equipment and overhead, due to the greater capacity of the warper and creel, and therefore the requirement for a less number of units of machinery. 110

While I have herein illustrated and described a preferred form of construction of 115 the creel and a preferred method of putting it into use, various modifications may be made in the structure and arrangement of its parts and its method of application to various processes of the textile art.

Therefore, without limiting myself to the exact embodiment of the invention as herein shown and described, I claim:

1. A creel comprising a frame, tension-devices carried on said frame, a plurality of 120

- supply-holders arranged adjacent said tension-devices and adapted to support supply-cops disposed with the axes of two adjacent cops pointing toward a single associated tension-device, and means for mounting the supply-holders to adapt them to be swung back out of position to facilitate the placing of the cops thereon and the doffing of the empty supply-carriers therefrom.
- 5 2. A creel for the purpose specified comprising a frame, tension-devices mounted at the front of the frame, supply-holders mounted at the rear of the frame and arranged to support the supply-cops carried by two associated holders to deliver successively to a single tension-device, means for normally maintaining the supply-holders with their cops in delivering position, and means for releasably retaining the supply-cops on the holders.
- 10 3. A creel for the purpose specified comprising a frame, tension-devices mounted at the front of the frame, supply-holders mounted at the rear of the frame and adapted to support the supplies in pairs with the axes of both supplies in each pair directed toward a single tension-device, means for mounting the supply-holders to adapt them to be moved back from delivering position to facilitate the placing of the supplies thereon and the doffing of the empty supply-carriers therefrom, and automatically-operated detent-means for normally maintaining the supply-holders with their supplies in delivering position.
- 15 4. A creel for the purpose specified comprising a frame having two opposite angularly disposed wings, tension-devices mounted at the front of the wings, supply-holders mounted at the back of the wings and arranged to support a plurality of cops of yarn associated in pairs with the two cops of each pair having their axes directed toward a single tension-device, and separators at the forward end of the creel arranged to guide the yarns leading from all of the cops to maintain them in banks corresponding to the rows of tension-devices extending longitudinally of the creel.
- 20 5. In a creel the combination of a plurality of supports, cop-holders swiveled on said supports, tension-devices mounted at the front of the cop-holders, and detent-means for normally maintaining the cop-holders in operative position to adapt them to support a series of supply-cops with each two adjacent cops in the series having their axes aligned with a single tension-device while permitting each of the cop-holders to be swung back out of position to facilitate the placing of the cop thereon and the doffing of the empty carrier therefrom.
- 25 6. In a creel the combination of a framework having a series of vertical uprights, a second series of uprights arranged in advance of the first series, tension devices carried on the uprights of the first series cop-holders projecting from opposite sides of the uprights of the second series and carrying spindles disposed in angular relation with their axes converging at one of the tension-devices, and means for normally maintaining the cop-holders in operative position while permitting them to be swung back to apply the cops thereto and to doff the empty carriers therefrom.
- 30 7. In a creel the combination of a framework comprising vertical uprights arranged in two series with one series spaced in advance of the other, tension-devices mounted on the uprights of the forward series, cop-holders swiveled on the uprights of the rearward series to adapt them to swing therearound, spindles carried by the cop-holders for supporting yarn-cops with their axes directed toward the tension-devices, and automatically-operated detent-means for normally maintaining the cop-holders with their spindles in operative position with relation to the tension-devices while adapting them to be swung back to facilitate the placing of the cops thereon and the doffing of the empty carriers therefrom.
- 35 8. In a creel the combination of a framework comprising opposite wings each having two series of vertical uprights with one series spaced in advance of the other, tension-devices on the uprights of the forward series, cop-holders on the uprights of the rearward series, means for retaining yarn-cops on the cop-holders with their axes directed toward the tension-devices and each two adjacent cops associated with a single tension-device, and automatically-operated means for maintaining the cop-holders with their cops in operative relation with respect to the tension-devices while permitting them to be swung back out of position to facilitate the placing of the cops thereon and the doffing of the empty carriers therefrom.
- 40 9. In a creel the combination of a framework comprising vertical uprights arranged in opposite series, tension-devices carried by the uprights of one series, cop-holders rotatable about the uprights of the other series, means to limit the rotative movement of the cop-holders, and automatically-operating detent-means for normally maintaining the cop-holders in position to adapt two associated cops to deliver to a single tension-device.
- 45 10. In a creel the combination of a series of vertical uprights, collars fixedly supported on the uprights, arms having hubs rotatable on the uprights and bearing against the collars, spindles carried by said arms for supporting yarn-cops, and detent-means between the arms and the collars for locating the arms in predetermined position while adapting them to be swung around to facilitate

- tate the placing of the cops thereon and the doffing of the empty carriers therefrom.
11. In a creel the combination of vertical uprights, collars fixed on said uprights and formed with grooves on their sides, cop-holders having hubs rotatable on the uprights above the collars and provided with detents adapted to engage the grooves in the collars to normally hold the cop-holders in predetermined position, and means on the cop-holders for supporting cops of yarn.
12. In a creel the combination of vertical uprights, a series of collars on each upright, cop-holders having hubs rotatable on the uprights with their ends resting against the collars, said cop-holders arranged in alternate relation to project from opposite sides of the uprights, means on the cop-holders for supporting yarn-cops, and means acting between the cop-holders and the collars to normally retain the yarn-cops in predetermined position while adapting the holders to be swung back to facilitate the placing of the cops thereon and the doffing of the empty carriers therefrom.
13. In a creel the combination of a series of vertical rods, collars fast on said rods and provided with stop-lugs projecting angularly from their sides, cop-holders having arms terminating in hubs rotatable on the rods and resting against the collars, means on the cop-holders adapted to contact with the stop-lugs on the collars to limit the swinging movement of the arms, and detent-means acting between the arms and the collars to normally maintain the cop-holders in predetermined angular relation with respect to the rods.
14. In a creel the combination of a framework, a series of tension-devices mounted at the front of the framework, a series of cop-holders mounted at the rear of the framework and carrying cop-spindles arranged in associated relation with two adjacent spindles directed toward a single tension-device, and cop-carriers adapted to be supported on the spindles and provided with means at their ends for holding a free length of yarn whereby the last end of one cop may be spliced to the leading end from the next associated cop to adapt the yarn to deliver to the tension-device successively from one cop and then the other.
15. In a creel the combination of a plurality of tension-devices, and a plurality of yarn-cops of a number double that of the tension-devices, said yarn-cops associated in pairs with the leading end of the yarn from one cop drawing through its respective tension-device and the last end of this cop spliced to the leading end of its associated cop to adapt the yarn to deliver successively first from one cop and then from the other to permit the creeling of a series of cops to replace the first exhausted cops without arresting the delivery from the reserve cops.
16. In a creel the combination of a framework comprising opposite wings, supply-holders supported on the rearward side of each wing, tension-devices supported at the front of the wings and arranged in horizontal rows in alinement with the axes of the cops on the supply-holders, and a plurality of separator-devices mounted on opposite sides at the apex end of the creel and having means for guiding the yarn leading from each horizontal row of tension-devices to maintain the ends in a series of banks.
17. In a creel the combination of a framework comprising opposite wings arranged in divergent relation, tension-devices mounted in horizontal rows at the front of each wing, cop-holders mounted at the back of each wing and arranged to support a series of cops with two associated cops having their axes directed to a single tension-device, a series of separators mounted at the apex end of the creel in alinement with the rows of tension-devices and provided with guiding-means for directing the yarn from the several rows of cops to maintain them in separate banks spaced one above the other.

In testimony whereof I hereunto affix my signature.

ERNEST A. DE WOLF.
